UNITED STATES PATENT OFFICE.

OLIVER B. SHALLENBERGER, OF ROCHESTER, PENNSYLVANIA.

REGULATOR FOR DYNAMO-ELECTRIC MACHINES.

SPECIFICATION forming part of Letters Patent No. 337,628, dated March 9, 1886.

Application filed December 5, 1885. Serial No. 184,791. (No model.)

To all whom it may concern:

Be it known that I, OLIVER B. SHALLENBERGER, residing at Rochester, in the county of Beaver and State of Pennsylvania, a citizen of the United States, have invented or discovered certain new and useful Improvements in the Regulation of Dynamo-Electric Generators, of which improvements the following is a specification.

10 In the accompanying drawings, which make part of this specification, Figure 1 is a diagrammatic view showing the manner of applying the auxiliary coils to a shunt dynamo-electric machine. Fig. 2 is a similar view 15 showing a modification of the auxiliary coils. Figs. 3, 4, 5 are similar views showing the manner of applying my invention to different kinds or classes of dynamo-electric machines.

The invention herein relates to certain improvements in the manner of winding the cores of the field-magnets of dynamo-electric machines, and has for its object the maintenance of a constant difference of potential in its work or external circuit, under variable 25 conditions of work in said external circuit.

An approximately constant electro-motive force can be maintained at the terminals of shunt-wound dynamos of the usual construction by so constructing and proportioning the 30 various parts that the resistance of the armature shall be low and that of the field-coils high relatively to the resistance in the external or work circuit; or the same result may be secured by the ordinary compound winding; 35 and this electro-motive force is the same throughout the main conductors, if their resistance be sufficiently low as compared with that of the work-circuit to be negligible. If, however, this resistance be increased to a 40 considerable amount, a loss of electro-motive force occurs at the outer extremities of the main conductors proportional to the amount of current passing, and hence a constant electro-motive force at the terminals of the dynamo no longer maintains a constant difference 45 of potential at the point of consumption with a varying current—as, for example, if an incandescent lamp were placed across the extremities of the mains, it would receive a current of the same electro-motive force as if placed across the terminals of the dynamo; 50 but if a large number of such lamps were

placed in the circuit the large quantity of current required to supply the lamps would cause a fall in the electro-motive force in the 55 work-circuit proportional to the increase in current. This fall in electro-motive force produces a corresponding decrease in the incandescence of the lamps; but they may be brought up to their normal incandescence by 60 increasing the electro-motive force of the generator sufficiently to compensate for the loss in the main conductors; hence, in a system of electrical distribution in multiple arcas, for example, incandescent lighting—it is 65 necessary to employ a generator so constructed that the electro-motive force may be increased with each increase in consumption of current in the work-circuit by an amount equal to the loss due to the resistance of the conductors, 70 and conversely to lower the electro-motive force with each corresponding decrease in the current consumed. These results may be effected either by the use of mechanical devices (operated or controlled by hand or by 75 the current in the work-circuit) or by so winding and proportioning the coils of the generator as to produce the desired regulation.

In compound wound dynamos of the ordinary type, in which the main current traverses 80 coils wound upon the field-magnets, it is possible to so proportion the coils as to produce a definite variation of electro-motive force with a definite variation of current or external resistance. This variation, however, is fixed for 85 a given machine at a given electro-motive force, and hence such a machine can only be employed upon a circuit in which the loss in the mains corresponds very nearly to the increase in electro-motive force due to the current traversing the series coils. These coils 90 also introduce a useless resistance into the main circuit.

The object of this invention is to so construct a dynamo as to make it readily adaptable to any circuit on which it may be placed by so winding and connecting its exciting-coils that the varying loss of electro-motive force between the extremities of the main conductors shall be automatically compensated by a 95 corresponding increase in field strength, and consequent increase in electro-motive force at the terminals of the dynamo, whatever may be the resistance of these mains, and conse-

quent drop of potential between the dynamo and point of consumption. Its peculiar features of advantage, therefore, are that no special proportioning of the coils of each machine to the circuit upon which it is to be used is required; and, further, the manner of arranging the coils and their circuits avoids the necessity of passing the entire current through the field-coils, which is a serious defect, owing to the resistance thus introduced into the circuit.

The shunt-wound dynamo A is of the usual form and construction, and has its high-resistance field-coils 2 and 2^a connected in shunt to the main terminals 3 and 3^a of the dynamo. On the cores of the magnets 1 and 1^a are also wound the auxiliary coils 5 and 5^a, also of high resistance relatively to main circuit, which may be arranged alongside of the main field-coils, as shown, or may be wound on top of such coils, or underneath the same. These coils are independent of each other, and the outer end or terminal of the coil 5 is connected by a wire, 9, of low resistance, to the outer terminal of the main conductor 7, and the opposite end of said coil 5 being connected to the positive terminal 3, to which the inner end of the main conductor 7 is also connected. The coil 5^a is correspondingly connected to the other main conductor, 8, by a wire, 10, of low resistance, and the negative terminal 3^a.

The action of the auxiliary coils 5 and 5^a is as follows: Suppose the generator to be running without doing any external work, but maintaining an electro-motive force of any given amount at its terminals, produced by the field-coils 2 and 2^a. This electro-motive force will exist equally throughout the entire circuit as long as no current passes, and therefore no current will pass through the coils 5 and 5^a, since there will be no difference of potential between the terminals 3 and 3^a and the outer extremities of the main conductors 7 and 8 by an amount equal to the current multiplied by the resistance, if the action of the coils 5 and 5^a be disregarded, while the electro-motive force at the terminals 3 and 3^a remains nearly constant. This drop of potential at the extremities of the main conductors correspondingly affects the lamps in the circuit; but in dynamos having the auxiliary coils 5 and 5^a the resistance in the main conductors and consequent difference of potential between the terminals 3 and 3^a and the extremities of the line produces a corresponding difference of potential between the terminals of the coils 5 and 5^a, the wires 9 and 10 being of comparatively low resistance, and the resulting flow of current is in such a direction and of such an amount that the field-magnets are further energized and the electro-motive force increased by an amount equal to the loss

in the main conductors. As the resistance in the work-circuit is further reduced by the addition of lamps, and the current consequently increased, the loss of potential in the main conductors is correspondingly increased, and a greater amount of current will pass through the auxiliary coils 5 and 5^a, which thus assist the field coils in producing a greater excitation in the magnetic field.

By properly proportioning the field and auxiliary coils they may be made to raise the electro-motive force at the terminals in proportional amounts to the degree necessary for the proper illumination of all the lamps in the working-circuit simultaneously. By cutting lamps out of the circuit a contrary effect is produced, the electro-motive force being reduced as the flow of current in the main conductors is reduced. Thus the regulation is maintained automatically, whatever may be the resistance of the main conductors or the amount of current passing, and the electro-motive force is always proportional to the current required in the work-circuit, the main field-coils being proportioned to give the initial field required for the least number of lamps used or amount of work to be performed, and the auxiliary coils proportioned to produce the additional field strength for the largest number of lamps and the greatest amount of work.

A small variable resistance, 12, can be introduced into the coil-circuits to adjust the field strength to the speed of the armature, which once adjusted will require no further change.

In lieu of arranging the coils 5 and 5^a independent of each other, as above stated, they may be connected in series with each other, the coil 5 being connected by a wire, 13, of low resistance, to the outer extremity of the main conductor 8, and the coil 5^a being connected to the terminal 3^a, as shown in Fig. 2. The auxiliary coils 5 and 5^a may be applied for a like purpose and with a like result to a compound wound dynamo, and also to a separately-excited dynamo, as shown in Figs. 3, 4, and 5, the coils being independent of each other or connected in series, as described in connection with shunt-dynamos; or, in the case of separately-excited dynamos, the auxiliary coils may be applied to the cores of the magnets of the exciting-dynamo, as shown in Fig. 5. In the latter case the coils 2 and 2^a of the main dynamo are connected in the usual manner to the terminals 14 and 14^a of the exciting-dynamo 15. The auxiliary coil 5 is connected at its ends by the low-resistance wire 16 to the terminal 3 of the main dynamo and the outer extremity of the main conductor 7, leading from the same terminal, and the coil 5^a is similarly connected by the low-resistance wire 17 to the terminal 3^a and the outer extremity of its main conductor 8. Any difference of potential between the ends of the main conductors 7 and 8 will cause an increased amount of current to pass through the auxiliary coils of

the exciter, thereby producing an increased excitation of its field of force and a corresponding excitation of the field of the main dynamo. The advantage of thus automatically proportioning the electro-motive force to the work to be done becomes evident when the saving in the cost of conductors is considered.

When the source of power is located at any considerable distance from the point of consumption, very large conductors are required to accomplish the necessary regulation in the ordinary way, or, in other words, to reduce the drop of potential within practical limits the weight of conductors should increase as the square of the distance; hence a point is soon reached where the cost of such conductors is prohibitive. If, however, a large drop of electro-motive force is permissible before the point of consumption is reached, it is only necessary to employ conductors of sufficient size to prevent undue heating, which is often only a small fraction of the former size. This large drop of potential between the points of generation and consumption is permissible where machines of the character above described are employed, the drop of potential on the line being always counterbalanced by a corresponding rise of electro-motive force at the generator through the whole range of current taken off.

The prominent characteristic of the invention herein is the automatic proportioning of the electro-motive force at the terminals of the dynamo to the current required in the working-circuit by the difference of potential in the main conductors between the points of generation and consumption, and thereby causing such difference of potential in the working-circuit to react through auxiliary coils in the field-magnets, so as to restore fully or approximately the loss or drop in electro-motive force, which would otherwise be occasioned thereby.

45 I claim herein as my invention—
1. In a system of electric distribution, the

combination of a field-magnet and the main coils thereof, auxiliary exciting coil or coils, main conductors connecting the terminals of the machine and the working circuit, and a shunt-circuit including the auxiliary coils and electrically connected to the terminals of the dynamo and the main conductors at or near where the same are connected with the working-circuit, the resistances of the auxiliary coils being suitably proportioned, so that any difference of potential in the main conductors between the points of generation and consumption will automatically increase or decrease the excitation of the magnetic field, substantially as set forth.

2. In a system of electric distribution, the combination of a field-magnet and the exciting coils thereof, and an auxiliary exciting coil or coils suitably connected with the extremities of either or both of the main conductors and adapted to automatically increase or decrease the excitation of the magnetic field in proportion to the difference of potential between the inner and outer terminals of the main conductors, substantially as set forth.

3. In a system of electric distribution, the combination of a dynamo-electric machine, main conductors connecting the terminals of the dynamo and the work-circuit, and an exciting coil or coils upon the field-magnets having its terminals connected, respectively, to a terminal of the dynamo and to one of the main conductors at or near its connection with the working-circuit, said exciting-coil being suitably proportioned, so as to automatically increase or decrease the excitation of the magnetic field in proportion to the difference of potential in the main conductors between the points of generation and consumption, substantially as set forth.

In testimony whereof I have hereunto set my hand.

OLIVER B. SHALLENBERGER.
